UNITED STATES PATENT OFFICE.

MARIO GIANINI, OF NEW YORK, N. Y.

MACHINE FOR FACILITATING PACKING.

1,102,493.

Specification of Letters Patent.

Patented July 7, 1914.

Application filed January 25, 1912. Serial No. 673,491.

To all whom it may concern:

Be it known that I, MARIO GIANINI, a citizen of the United States, and resident of New York city, in the county of New York and State of New York, have invented certain new and useful Improvements in Machines for Facilitating Packing, of which the following is a specification.

This invention relates to a machine the purpose of which is to facilitate the filling of receptacles, and which is particularly useful under conditions where a great number of receptacles are to be filled with small quantities or portions of different kinds of goods, such as different kinds of candies. Such boxes are frequently packed with the different kinds of candies arranged in layers. It is the usual practice to place a number of these boxes on a table or several tables and the operator fills the boxes layer by layer. This arrangement necessitates the use of a very considerable floor space entailing a large expense in rent.

The object of this invention is to produce a machine occupying a small floor-space and which will enable a great number of receptacles, such as candy boxes, to be presented to the operator in succession so that the different layers, or different kinds of candies, may be conveniently placed in the boxes. In the operation of the machine, the operator places a layer of a certain kind in the boxes which are simultaneously presented to her, and then advances the mechanism of the machine to present the next set of boxes. A layer of the same kind of candy is then placed in that set of boxes, and so on, until all the boxes in the machine have been provided with this layer. A supply of another kind of candy is then placed convenient for the operator and the boxes are advanced again in succession to receive the new layers in the same manner as that described. The receptacles or boxes are held upon carriers or hangers, held within a case of vertically elongated form, and the carriers present themselves successively to the operator. On account of the vertically elongated form of the case the machine enables a great number of the receptacles to be handled and filled upon a relatively small floor space.

A further object of the invention is to provide means for supporting and guiding the carriers so that the receptacles will be conveniently presented to the operator and held stationary while the receptacles are receiving the candies.

A further object of the invention is to provide improved means for holding the supply receptacles while the boxes are being packed.

The invention consists in the construction and combination of parts to be more fully described hereinafter and particularly set forth in the claims.

In the drawing which fully illustrates my invention, Figure 1 is a side elevation of a machine constructed in accordance with my invention. Fig. 2 is a plan. Fig. 3 is a front elevation showing part of the front of the machine.

Referring more particularly to the parts, 1 represents the case or frame of the machine which is built of metal plates, and is of box form, and vertically elongated as shown. Within this case I provide two endless chains 2 disposed near the side walls 3 of the case; and these chains are guided over sprocket wheels 4, which are supported from the cover 5 of the machine on suitable brackets 6. Near the floor these chains are guided under similar guide wheels or sprockets 4 which are supported on brackets 6 near the bottom of the machine, as indicated. The forward wall or plate 7 of the machine is provided with an opening 8 and the chains 2 are guided out through this opening to form loops 9 passing around guide pulleys or sprockets 10 mounted on suitable brackets 11 attached to the front of the case, as shown. And on the inner side of the case near these openings guide pulleys or sprockets 12 are provided which guide the chains in passing through the opening. Between the chains I provide a plurality of hangers or carriers 13, which are in the form of swings or hammocks supported upon pins 14 which are formed on the links of the chains 2. These carriers are disposed an equal distance apart along the chains, as shown. Each carrier or hanger has ends 15, which are preferably in the form of triangular plates offset near the

pivots 14, and between these end plates horizontal bottom plates 16 are provided which support the receptacles which are to be filled. These bottom plates, at the ends of the carriers, are provided with projecting dogs or lugs 17 which extend beyond the end plates 15, as shown. The direction of movement of the chains is that indicated by the arrows on Fig. 1, that is, the forward 10 runs of the chains pass upwardly. In this way the carriers are made to pass out through the opening 8 into a receiving position, that is, a position such as that indicated by the carrier 13^a at the front of the 15 machine. It should be understood that these carriers are merely suspended from their pivot pins 14. In order to hold the carriers 13 fixed against swinging on their pivots when presented to the operator, that 20 is, when in their receiving position, I provide guide cams 18 and 19, which are disposed on each side of the machine and mounted on suitable brackets 19^a attached to the front of the case. The cams are 25 attached to yokes 19^b seated on the brackets 19^a. These cams are of the form shown most clearly in Fig. 1. The rear cam 19 is of substantially bow shape so as to present a curved guiding lip 20 on its lower end, and the forward cam 18 is in the form of a 30 vertically elongated plate the lower end of which is bent outwardly to form guide lip 21. As the carrier 13^a passes up into the position in which it is illustrated in Fig. 1 its 35 dogs 17 are guided by the lips 20, 21, so as to pass inside the short vertical channel or guideway which is formed between the guide cams, as shown. When the lugs or dogs 17 are in this position evidently they 40 will hold the carrier 13^a fixed, that is, they will prevent any swinging movement.

Just above the location of the carrier 13^a I provide a service shelf 22 which is preferably disposed in an inclined position and attached to the forward wall of the case. The 45 lower edge of this shelf is provided with a cleat 23 which prevents the stock boxes or receptacles 24 from sliding off. Just above the service shelf 22 I provide a plurality of 50 supply shelves 25 which are also attached to the forward wall of the case, and these latter shelves are adapted to receive supply boxes 26 holding candies of different kinds.

In order to enable the chains 2 to be advanced, the foremost pulleys 4 at the upper end of the case are provided with shafts 27 which project through the side walls and carry sprocket wheels or pulleys 28. Over these pulleys 28 endless chains 29 run, passing up from sprocket wheels or pulleys 30 55 mounted on the ends of a cross-shaft 31 mounted directly under the shelf 22. On the end of this shaft 31 there is provided a bevel gear 32, at the right of the machine, 60 which meshes with a bevel pinion 33 carried

on a horizontal shaft 34 mounted in a suitable bracket 35, as shown in Fig. 2, and provided with a crank 36 for rotating the shaft. This crank 36 is within convenient reach of the operator who may sit upon a bench or 70 stool 37 in front of the machine and in a convenient position for filling the boxes 38 held on the carrier 13^a. The gearing driven by this crank 36 and the sprocket wheels or 75 pulleys 28 are arranged so that several turns of the crank are required to advance the next carrier 13^b into the operating position before the case. From this arrangement it will readily be seen that a very small force 80 is required to be applied to the crank.

In operating the machine the operator places a box or boxes 24 on the service shelf 22 holding a certain kind of candy. When a layer has been placed in all the receptacles 38 on one hanger or carrier 13, the next 85 hanger is advanced until all the receptacles within the case are provided with the same layer. A box having a different kind of 90 candy is then placed on the service shelf 22, and this operation is repeated until the boxes have all been completely filled. The covers are then applied and the filled boxes are then wrapped and removed.

Filling candy boxes as described is desirable by reason of the fact that the open 95 boxes are inclosed in the case during the operation and to a considerable extent kept from the dust which would deposit on them if they were otherwise exposed, as on filling tables.

The use of this invention also insures a compliance with statutes requiring the operators to be seated while working. The machine also results in great economy in cost of packing as it increases the output of 105 each operator about 48% as compared with packing on tables in the usual way.

Having described my invention what I 110 claim and desire to secure by Letters Patent is:—

1. A receptacle holding machine comprising a frame, a pair of endless chains, a plurality of carriers attached substantially equidistant on said chains, means for guiding said chains to form loops outside of said frame, said carriers having projections at the ends thereof, and means near the forward side of said frame to advance said chains, and fixed cams adapted to receive said projections when said carriers pass 115 around said loops, and adapted to hold said carriers against swinging upon their pivots.

2. A machine for facilitating the filling of candy boxes comprising a case, a pair of endless chains, guide pulleys for said chains 120 within said case, a pair of guide pulleys outside of said case adapted to guide said chains outwardly to form loops on the exterior of said case, a plurality of carriers pivotally supported between said chains, 125

130

means for advancing said chains to advance
said carriers successively into a filling po-
sition between said loops, and means near
said loops for holding said carriers against
5 swinging when the candy boxes carried
thereby are being filled.

Signed at New York city in the county of

New York and State of New York this 22nd
day of January A. D. 1912.

MARIO GIANINI.
